UNITED STATES PATENT OFFICE

168,650

ANIMAL CRATE

Robert K. McKee, Los Angeles, Calif.

Application April 25, 1950, Serial No. 9,464

Term of patent 14 years

(Cl. D12—2)

To all whom it may concern:

Be it known that I, Robert K. McKee, a citizen of the United States, residing at Los Angeles, county of Los Angeles, State of California, have invented a new, original, and ornamental Design for an Animal Crate, of which the following is a specification, reference being had to the accompanying drawing, forming a part hereof.

Fig. 1 is a perspective view showing the front, one side, and top of an animal crate showing my new design.

Fig. 2 is a side elevational view.

Fig. 3 is a rear elevational view.

I claim:

The ornamental design for an animal crate, as shown.

ROBERT K. MCKEE.
